CLAIM

The ornamental design for a shelf and mirror shelf combined with mirror, as shown and described.

DESCRIPTION

FIG. 1 is a perspective view of a shelf combined with mirror showing our new design;

FIG. 2 is a front view thereof;

FIG. 3 is a rear view thereof;

FIG. 4 is a side view thereof;

FIG. 5 is another side view thereof;

FIG. 6 is a top view thereof; and,

FIG. 7 is a bottom view thereof.

The broken lines illustrating portions of a shelf combined with mirror form no part of the claimed design. The dash-dot broken lines define the bounds of the claimed design and form no part thereof. Oblique shade lines show a translucent or transparent material.
